UNITED STATES PATENT OFFICE.

HENRY R. GILSON, OF BADEN, PENNSYLVANIA, ASSIGNOR TO NATIONAL METAL MOLDING COMPANY, OF PITTSBURGH, PENNSYLVANIA, A CORPORATION OF PENNSYLVANIA.

CONNECTOR FOR WOOD TO METAL MOLDING.

1,134,120.

Specification of Letters Patent.

Patented Apr. 6, 1915.

Application filed December 12, 1913. Serial No. 806,295.

To all whom it may concern:

Be it known that I, HENRY R. GILSON, residing at Baden, in the county of Beaver and State of Pennsylvania, a citizen of the 5 United States, have invented or discovered certain new and useful Improvements in Connectors for Wood to Metal Molding, of which improvements the following is a specification.

10 In buildings provided with electrical conductors for lighting, etc., it is frequently desirable to extend the circuit to various points, as for additional lights. The modern practice both for economy and safety, is 15 to carry the conductors of the extended circuits through surface metal molding regardless of the kind of conduits used in the original installation; and, since a large part of the surface conduits formerly used is 20 wood molding, the circuits are then extended from wood to metal molding.

The object of my invention, which relates to installations of the character described, is to provide a connector adapted to extend 25 from the end of a section of metal molding to an adjoining section of wood molding, and to carry the conductors from one to the other in a manner complying with all the conditions of such installation.

30 It is a further object of my invention to provide a connector that may be used to extend circuits both from the end and side of wood moldings to metal moldings.

In the accompanying sheet of drawings, 35 which forms part of my specification, I have illustrated the preferred embodiment of my invention, and its application to circuits extended both from the side and ends of wood molding.

40 Figure 1 is a plan view of a complete installation; Fig. 2 is a longitudinal sectional view taken on the line II-II, Fig. 1; Fig. 3 is a perspective view, to enlarged scale, of the connector block alone, showing the top 45 and the end adjacent to the wood molding; and Fig. 4 is a similar view of the same block, but showing its bottom and the end adjacent to the metal molding.

In the several figures like numerals are 50 used to designate like parts.

The wood molding illustrated herein is of the usual type comprising a body portion 1 and a cover 2. The body portion is provided with separated grooves 3, 3^a adapted to re-

ceive conductors 4, 4^a, and the cover is secured to the body portion after the conductors have been laid in position. The metal molding consists of base and cover portions 5 and 6, each semi-elliptical in form, the cover being adapted to snap upon the base. 60 However, it will be understood that various other forms of metal molding may be employed in the same manner as that shown.

In extending a circuit from the wood molding, wherein the conductors are required to be carried in separate grooves, to metal molding, wherein the conductors may be side by side, it is necessary in the completed installation that a partition extend 70 between the conductors until they enter the metal molding, and in making the installation it is required that the conductors be laid in place, rather than drawn through any part of the conduit. The connector which I provide is applied after the conductors have been laid in place; it affords a 75 converging separate and inclosed path for each conductor; and protects their insulation against abrasion by the end edges of the metal molding.

The connector is illustrated particularly in Figs. 3 and 4, and consists of an arch-shaped block of insulating material, preferably porcelain, having a roof portion 7 and legs 8. A tongue 9 projects from the center 80 of the roof and forms, with the legs 8, a pair of grooves 10 which converge from the wood molding to the metal molding side of the block. A slot 11, open at both ends, is formed within the tongue, and is provided 85 with a bead or shoulder 25. The metal-molding end of the block, as shown particularly in Fig. 4, is provided with a seat 13 against which the end of the metal molding abuts, thereby preventing the abrasion 90 of the conductor insulation by the end edges of such molding.

Referring now to the installations wherein the connector is employed, the base 5 of the metal molding may be secured, by means of a screw 14, to a plate 15, which in turn is attached to a wall or support by means of a screw 16; and the branch conductors, 17 and 17^a, electrically connected to the conductors 3 and 3^a, may be laid in the position 100 particularly illustrated in the lower left hand portion of Fig. 1, that is, converging 105 from their point of connection to such con-

ductors. The connector block may then be secured to the plate 15 by means of screws 18 extending one through each hole 26 of the legs 8. When the connector is placed in position, the conductors 17 and 17^a will lie one within each groove 10 of the block, and the metal molding will extend into the seat 13. The complete installation of the connector, when applied to a circuit extended from the 10 side of a wood molding, is illustrated in the upper left hand portion of Fig. 1; and, in addition to the above detailed description, is effected by securing the porcelain cap 19 to the connector block by means of a screw 12 15 provided with a nut 28 which engages the shoulder or bead 25 of the slot 11, as seen in Fig. 2. The cap 19 and the splicing block 20 beneath it are such as have been ordinarily used when branch circuits have been 20 carried in wood molding. They are details of construction usually required by the underwriters for splices and similar connections and therefore need not be described herein.

25 When it is desired to extend the circuit from the end of wood molding, rather than from the side thereof, the arrangement may be such as is illustrated in the right hand portion of Fig. 1. The same connector is 30 used in the same manner and for the same purpose in each instance, the only difference being that in a side connection to the plane-faced ends of the connector, legs 8 (seen particularly in Fig. 3) are adjacent to 35 the side of the wood molding, while in the end connection they are adjacent to the end thereof. In the end extension, the cap 19^a and splicing block 20^a are the same as used heretofore in effecting a splice in conductors 40 carried in continuous wood molding, the cap 19^a being attached to the connector by the screw 12 and to the wood molding 1, 2 by a screw 21, thereby indirectly attaching the connector to the molding.

45 I claim as my invention:

1. The combination with adjoining sec-

tions of wood and metal moldings carrying electrical conductors in circuit, of a connector between said sections and at the end of said metal molding, said connector consisting of an arch-shaped block of insulating material having a tongue extending from the roof thereof and forming with the legs of said block a pair of conductor-receiving grooves diverging from the end of the metal molding, and means for attaching the connector through said tongue to the wood molding.

2. The combination with adjoining sections of wood and metal moldings carrying electrical conductors in circuit, of a connector at the end of the metal molding and extending to the wood molding, said connector consisting of an arch-shaped porcelain block having a central tongue extending from the roof thereof and forming with the legs of said block a pair of conductor-receiving grooves diverging from the end of the metal molding, and a seat in said block for the end of the metal molding, said seat extending beyond the outer sides and bottoms of said grooves.

3. The combination with adjoining sections of wood and metal moldings carrying electrical conductors in circuit, of a connector between said sections and at the end of said metal molding, said connector consisting of an arch-shaped block of insulating material having a tongue extending from the roof thereof and forming with the 75 legs of said block a pair of conductor-receiving grooves communicating with the end of the metal molding, and means for attaching the connector through said tongue to the wood molding.

In testimony whereof I have hereunto set my hand.

HENRY R. GILSON.
